UNITED STATES PATENT OFFICE.

PERCY H. THOMAS, OF MONTCLAIR, NEW JERSEY, ASSIGNOR TO COOPER HEWITT ELECTRIC COMPANY, OF NEW YORK, N. Y., A CORPORATION, OF NEW YORK.

GAS OR VAPOR CIRCUIT-BREAKER.

No. 919,264.

Specification of Letters Patent.

Patented April 20, 1909.

Original application filed June 27, 1903, Serial No. 163,307. Divided and this application filed April 25, 1905, Serial No. 257,304. Renewed September 4, 1908. Serial No. 451,738.

To all whom it may concern:

Be it known that I, PERCY H. THOMAS, a citizen of the United States, and resident of Montclair, county of Essex, State of New Jersey, have invented certain new and useful Improvements in Gas or Vapor Circuit-Breakers, of which the following is a specification.

The object of the present invention is to provide a circuit breaker by means of which an electric circuit can be interrupted without danger of the formation of a destructive arc.

It is especially adapted to use in connection with alternating current circuits.

The significant feature of the invention is that the circuit is broken between surfaces inclosed in an exhausted chamber. I generally employ mercury as the means for closing the circuit inside the chamber and cause the rupture of the circuit by separating the body of mercury into two or more parts, whereby any part that is formed extends between two surfaces of mercury. When such a circuit breaker is included in an alternating current circuit, the arc is readily ruptured when the current momentarily ceases at the zero point of the wave and cannot start again, whereby it is effected that no injurious rise of potential is caused in the outside circuit.

I have illustrated my invention in the accompanying drawings, in which—

Figures 1 and 2 illustrate a form of circuit breaker; and Fig. 3 is a vertical section of a modification.

The form of circuit breaker illustrated in Figs. 1 and 2 has the peculiarity of forming its own vacuum when passing from the closed to the open position, as will presently appear. In this form of apparatus I employ a shell, 8^a, preferably of iron within which is held a tube, 9^a, of glass, porcelain or other good insulating material. The tube 9^a is open at the bottom and when the tube is in its lowermost position inside the shell 8^a both the tube and the neutral space between the tube and the shell are nearly filled with mercury, as shown in Fig. 3. At its upper end the tube 9^a is spread slightly and fitted with a sleeve, 10, of iron or other conducting material, the said sleeve being itself provided with an internal ring, 11, on which rests a valve, 12, of any suitable rigid material. To the top of the shell, 10, is secured a flanged

piece or cover, 13, fitted with an eye-piece, 55 14, constituting a handle.

The parts last described, including the shell, the cover, and the handle, form a cap for the tube 9^a by means of which the latter can be lifted. The circuit wires are connected, respectively, to the shell 8^a, as shown at 15, and to the flanged piece 13, as shown at 16. In the closed position the circuit passes by way of the shell 8^a and the mercury to the sleeve 10 and the flanged 60 piece 13, and thence to the other side of the circuit.

To break the circuit, it is only necessary to lift the tube 9^a through the medium of its cap and the eye-piece 14, whereupon the mercury will descend in the annular space between the tube and the shell 8^a until the pressure of the air upon the mercury in the annular space has carried the mercury in the tube 9^a to the barometric height, after which 70 any further lifting of the cap and tube will cause a rupture of the circuit between the valve 12 and the mercury in the tube. The cap and tube may then be lifted to a point such as is indicated in Fig. 2 where the space 75 between the check valve 12 and the surface of the mercury opens a suitable space which is practically a high vacuum. It is sufficient that the check valve 12 should furnish a perfect seal only for an instant during the lifting process, so that a momentary vacuum shall 80 be formed for extinguishing the arc at the first alternation. After this time the necessity for the perfect seal no longer exists, as 85 there would be no danger of a restoration of the circuit even should the air leak in past the valve. By this statement, it is not intended to exclude the possibility of an approximately perfect seal at all times at the check valve 12. The said valve will generally 90 be of conducting material, but it will be understood that electrical contact need not be broken between the mercury and the valve 12, but may be broken between the mercury and some other part of the apparatus. In 95 Fig. 3 the same principle is illustrated, except in certain particulars which will presently be explained. Here the shell 8^a is not so long as that shown in Figs. 1 and 2. The shell is formed into a cup shape at the top, 100 as shown at 17, and within it is placed a flanged ring, 18, which rests upon a washer, 19, as shown. The washer may be of soft

rubber or other suitable material, and it is fitted rather closely around the glass tube 9^a so that any mercury which tends to pass down into the annular space between the 5 tube 9^a and the shell 8^a will have to go very slowly. Owing to the conditions described, the air pressure will not act to raise the mercury in the tube 9^a to the barometric height, for which reason the apparatus illustrated in 10 Fig. 3 may be made shorter than that shown in Fig. 2, and the necessary movement of the tube in order to protect the circuit may be made smaller. The tube 9^a is flanged at the 15 top and rests upon the inner portion of the flanged ring 18 so as to be carried up thereby when the said ring is lifted. The eye-piece 14 is connected to a cross-bar, 20, at the top of the flanged ring 18 within which ring is secured by a screw thread or other means, a 20 second flanged ring 21 on which a check valve 22 rests. This check valve 22 has a tubular extension, 23, dipping down into the mercury in the tube 9^a. I provide suitable guide rods, 24, 24, which prevent a lateral movement of the cap during the lifting 25 process.

It will be understood that the herein described circuit breaker may be used in circuits carrying currents naturally varying, 30 whether or not the currents drop to zero or to a point higher than zero but below the carrying limit of the circuit breaker.

This application is a division of my application Serial Number 163,307, filed June 35 27, 1903, in which claims are made upon certain features of my invention.

I claim as my invention:—

1. In an electric circuit-breaker, an inclosing vessel, a movable element consisting of a 40 conducting liquid, a vertically movable tube immersed in said movable element, a conducting valve for closing the upper end of the tube and making contact with the liquid in the closed position of the circuit-breaker, and 45 means whereby the tube and its connected parts may be moved, whereby on a sufficient movement of the tube, a separation of contact surfaces will take place and a vacuum be formed in the circuit-breaker.

50 2. In an electric circuit-breaker, an inclosing vessel, a movable element consisting of a conducting liquid, an insulating tube immersed in the said element, a check-valve of conducting material closing the upper end of 55 the tube and making contact with the liquid in the closed position of the circuit breaker, and means whereby the tube can be lifted for creating a vacuum in the circuit breaker, and for separating the contacts within the 60 vacuum.

3. In an electric circuit breaker, a gravitationally controlled movable element, a cham-

ber containing the same, a plurality of circuit terminals coöperating with the said movable element, and means capable of being operated mechanically whereby a vacuum can be created within the chamber and the circuit broken in the vacuum. 65

4. In an electric circuit-breaker, a gravitationally controlled movable element, a chamber inclosing the same, a plurality of circuit terminals coöperating with the said movable element, a valve sealing the said chamber, means for lifting the chamber and operating the said valve to create a vacuum in the 70 chamber and to break the circuit in the vacuum. 75

5. In an electric circuit breaker, a movable element consisting of a conducting liquid, a suitable chamber inclosing the same, a plurality of circuit terminals connected with the liquid element, and a check valve closing the chamber, the height of the liquid being such as to constitute a temporary seal for the check valve on open position. 80

6. In an electric circuit breaker, a tube containing mercury, and a circuit terminal electrically connected with the mercury, a tube surrounding the first named tube with an annular space between, means for lifting the inner tube, and creating a vacuum therein, and for separating the contacts within the 90 vacuum.

7. In an electric circuit breaker, a movable element consisting of a conducting liquid, an inner tube surrounding a portion of the said liquid, an outer tube inclosing the said inner tube and the liquid, means for causing relative longitudinal movement between the inner and outer tubes, and means for sealing the inner tube whereby on moving the inner tube longitudinally a vacuum will be formed and a rupture of the circuit will take place inside the vacuum. 95

8. In an electric circuit breaker, a conducting liquid, an inner tube inclosing a portion thereof, and an outer tube inclosing the liquid and the inner tube, a seal for the inner tube, and means for causing relative longitudinal movement between the two tubes, the cross-section of the inner tube being such in comparison with the cross sectional area between the two tubes that the relative movement between the two tubes need only be a small one in order to create a vacuum and to 100 cause a separation of the contacts inside the 110 vacuum.

Signed at New York, in the county of New York, and State of New York, this 17th day of April A. D. 1905.
